Application May 16, 1933, Serial No. 671,322

19 Claims. (Cl. 38—41)

My invention relates to improvements in garment presses and by garment presses I include the type of presses generally known in the trade as garment presses and also laundry presses which also press garments.

This invention relates particularly to presses having a pair of pressing members, one stationary and one movably connected to the press frame.

An object of my invention is to provide a garment press with a man-power operated foot or hand mechanism for the actuation of the press and a supplemental fluid actuated power mechanism for supplemental actuation of the press especially for particularly heavy work and my invention particularly relates to the combination of the various specific means I employ for this purpose.

One feature of my improved construction relates to the fact that the application of the power mechanism is obtained through a bar lever which operates only to transmit the force of the power medium after the closing of the press to an intermediate pressing position by man power has resulted in raising a rigid means against the center of said bar-lever in order that the power mechanism may pivot said bar-lever to exert greater pressure on the pressing lever and to provide a construction, whereby if the power actuated means be actuated prior to the bar-lever being made into a lever by providing a rigid pivot point therefor as just described, said lever will merely pivot on the pressing lever without the application of any power thereto. I thus provide a high safety factor as accidental application of power will not dangerously apply pressure to or cause motion of the pressing lever with the press open or unless the press has been closed and locked in an intermediate man power pressing position by operation of the man power means to bring said bar-lever into a position to function as a lever, thus making it practically impossible for the operator to suffer from the accidental application of power. By employing my improved bar-lever I am enabled to provide a construction which will readily function as a rigid bar on actuation of said pressing lever by man power to close the pressing members to an intermediate operative position and which when in said intermediate position may function as a lever to transmit power from a fluid pressure piston to said pressing lever with increased leverage, if desired.

One feature of my improved construction lies in the use of a bar to connect the movable press

member to the press mechanism for hand or treadle operation, said bar functioning as a lever for supplemental fluid pressure power after the press has been closed and locked by hand or by treadle operation in an intermediate position, said manual or treadle closing of the press swinging into place a rigid means on which the bar may pivot as a lever, said rigid means being displaced when the press is open, thereby providing a very high safety factor as accidental application of fluid power with the press open cannot transmit motion to the movable press member, such motion requiring rigid means in connection with a lever, said means being present only when the press has been previously by hand or by treadle operation closed and locked in an intermediate pressing position.

In this description three positions are ascribed to the movable pressing member. When the movable press member is separated to full extent from the rigid press member, the press is described as open. When the movable press member is by hand or by treadle brought by man power into contact with the rigid press member and locked without the application of fluid power, the press is described as in intermediate position. When the movable press member is advanced by power means from the locked intermediate position into closer contact with the rigid member, the press is described as in closed position.

By employing my improved construction I include in the mechanism a bar for advancing the movable press member from open to intermediate position, said bar functioning as a lever for further advancing the movable press member from intermediate to closed position.

A further object of my invention is to provide a mechanism which makes it possible to apply a very powerful pressure to the stationary and movable pressing forms without hampering the operation of the press as a man power operated unit for light pressure only. This is a decided advantage in garment manufacture where the operations require a convenient and optional variation in pressure.

A further feature of my invention is to provide a construction wherein the attachment of a bar lever which is in effect a combination bar and lever to the fluid pressure actuated power mechanism is made in such a way as to increase the pressure power or leverage exerted by the fluid pressure actuated power mechanism.

A further feature of my invention relates to improvements in pressure lock and relief mechanism for the man power actuation of pressing

machines and by man power I mean operation by man power whether foot, hand or other part of the body. This feature of my invention is employed where a toggle mechanism is employed for increasing the leverage exerted by the foot lever and transmitted by the pressing lever to close the press and preferably includes an upper toggle member attached directly or indirectly to said pressing lever, a lower toggle member attached to the frame, a rear toggle member pivoted to a point on said lower toggle member and a front toggle member pivoted on the frame at a point intermediate the ends thereof and having its rear end connected to the front end of said rear toggle member. Said toggle mechanism includes the treadle pivotally mounted on said frame and means pivotally joining said treadle with the front end of said front toggle member, whereby on depression of said treadle said toggle mechanism may function to raise the bar lever then functioning as a bar to pivot the pressing lever to an intermediate pressing position. Types of toggle mechanism connected to a point on the power arm of the pressing lever are old, but this feature of my invention relates to the specific type of means I employ to lock and hold the front toggle member in a locked position past the dead center line of the points of jointure of said front and rear toggle members. To this end a locking lever is pivoted to the frame and having its front end fixed against clock-wise rotation by a bracket adjustable on the front of the machine and having a free rear end adapted to contact the rear end of the front toggle member and limit its clock-wise rotation in accordance with the position of the locking lever. By adjustment of the bracket stop on the front of the machine (which is in a much more accessible and convenient position than adjustable stops of this description on presses heretofore designed), the locking position of the front toggle member past its dead center may be readily adjusted. This feature of my invention therefore relates to the specific type of means I preferably employ for adjusting, in its intermediate man power actuated pressing position, from the front of the machine, the locking position of the toggle mechanism after the rear end of the front toggle member has passed dead center. The locking point of the press mechanism in the intermediate position with respect to the amount of hand or treadle pressure desired from the front of the machine is adjusted through restricting the motion of the front toggle member by the locking lever after it has been advanced slightly beyond dead center so that the reaction of the press will hold it in position. The improved locking lever may also function as a toggle release in lowering the front toggle member past its dead center in which case a release treadle may be attached to the front end thereof adapted to pivot the rear end of said locking lever downwards to abut said front toggle member to knock it past its dead center to release the toggle mechanism to release the press on depression of the foot release treadle. Attachment of said release treadle to the locking lever may be optionally made through a lost motion connection, and preferably through a lost motion connection when the release treadle is attached to a rocker arm operated valve action as hereinafter described.

A further feature of my invention relates to the means I preferably employ for controlling the actuation of the fluid pressure actuated power

mechanism and comprises a fluid pressure control valve mechanism for garment and laundry presses having particular relation to the type of presses which are closed by man power and with heavy pressure being effected by fluid actuated power means after the press is closed and locked by hand power. 5

An object of this feature of my invention is to eliminate the possibility of unlocking the press while under heavy pressure as the result of the recoil which is dangerous to the operator and harmful to the press mechanism. This feature of my invention thus provides a means for eliminating recoil through the use of a double treadle control. I provide a treadle for opening a valve 10 suitably placed to allow the flow of fluid power to the power operating means. I also provide a second treadle which, through its connection to the locking lever described above is the only 15 means for opening the press and by attaching the exhaust pressure valve to this treadle so that the exhaust valve action is positively related to the treadle motion, and in addition timing the motion of the associated parts so that before the treadle control functions to mechanically open 20 the press, the pressure valve will have released all external fluid pressure prior to man power pressure release action. Said valves and treadles are reciprocally connected by a rocker arm, the specific function of the exhaust treadle being first 25 to close the inlet valve, second to open the exhaust valve and third to open the press through a lost motion connection which allows the first two just mentioned operations to be completed 30 by a partial depression of the treadle before full depression of the treadle can complete the third. This invention includes having the power treadle linked to the exhaust treadle through a rocker arm so that depression of the power treadle will always close the exhaust valve before opening the 35 inlet valve and prevent loss of valuable fluid pressure and also so that fluid pressure will be maintained throughout the duration of the pressing action without loss of power due to leaks in the press power system. 45

A further feature of the power mechanism employed is to furnish an equal amount of linear pressure on the material pressed regardless of the thickness of the material. By this feature I am enabled to prevent button crushing and breaking out of threads on button holes on thick materials being pressed. 50

Further features of my invention relate to the general combination of all of the operating parts hitherto described, namely, of providing a positive 55 and readily adjustable lock adjustable from in front of the machine for adjustably locking the man power operated power mechanism in a raised locked intermediate position and with the upper and lower toggle members substantially rigid to 60 serve as a pivot for the bar lever thereon and with the fluid pressure actuated power mechanism later functioning through the tilting of the bar lever to apply power to the pressing forms and with the valve mechanism control for the application of fluid pressure to and away from said power mechanism being so arranged and connected as to close the outlet from the power mechanism prior to admission of any inlet or fluid pressure thereto and the power release mechanism being so connected to the man power operated release mechanism as to successively close the inlet valve to said power mechanism and open the exhaust valve thereof during the lost motion 70 75 75

of the outlet and release treadle so arranged that when the operation of the release of the power mechanism is completed, the man power operated mechanism may be consecutively broken to open the press and thereby providing an operative combination in combination with the lost motion and the means for breaking the man power pressure prior to opening the press.

These and such other objects of my invention as may hereinafter appear will be best understood from a description of various embodiments thereof, such as are shown in the accompanying drawings.

In the drawings, Fig. 1 is a central section of a standard type of garment press constructed in accordance with my invention showing the pressing members and mechanism thereof in open position.

Fig. 2 is a central section similar to Fig. 1 showing the pressing members and mechanism thereof in a man power actuated closed intermediate position.

Fig. 3 is a plan view of the rear end of the pressing lever and attached parts thereof.

Fig. 4 is a front elevation of a lower portion thereof illustrating particularly the foot levers and valve mechanism control for the power mechanism.

Fig. 5 is an enlarged detailed central sectional view of the pressing lever and associated parts showing the cylinder in section, and also showing in broken lines the position of the parts when full fluid pressure is used.

Fig. 6 is a view generally similar to Fig. 5 of the rear end of the pressing lever and associated parts of a slightly different embodiment of my invention illustrating a slightly different form of connection between the power mechanism and the pressing lever.

Fig. 7 is a sectional view generally similar to Fig. 5 showing the rear end of the pressing lever and associated parts of a still further modified form of my invention illustrating a different type of connection between the power mechanism and pressing lever.

In the drawings, wherein like characters of reference indicate like parts throughout, 10 generally indicates a standard type of garment press having the different features of my invention incorporated therein. Said press includes a frame 12 having a front portion on which the stationary pressing form 14 is mounted and a rear portion extending upwardly on which the pressing lever 16 is preferably pivotally mounted as at 18. The pressing lever 16 has the pressing form 20 mounted on the work arm 22 thereof so as to be movable therewith and in the embodiment of my invention shown the power arm 24 of said pressing lever 16 is provided with the stop 26 projecting laterally from the upper portion of the rear end thereof for a purpose to be explained, although it is obvious that if desired said stop 26 may be omitted.

A usual type of man power operated mechanism is provided for the relative closing of said pressing forms 14 and 20 to an operative intermediate pressing position and preferably means is also provided for locking said pressing forms in an intermediate pressing position after the man power actuation thereof to said position. As explained hitherto I employ the term "man power" to mean operated by the genus man whether by the foot or hand thereof, and for this purpose the means for man power actuation of said press may include a handle 28 mounted on the movable

pressing lever for the hand actuation thereof, or a treadle 30 pivotally mounted as at 32 on the rear end of said frame to actuate through a standard type of toggle mechanism 34 or other means, the power arm 24 of said pressing lever 16 to pivot the movable pressing lever 20 into pressing relationship with the stationary form 14.

As stated hitherto, one feature of my invention relates to a bar lever 36 adapted to receive the thrust of the toggle mechanism 34 to function as a bar for man power closing of the pressing lever 16 to an intermediate pressing position and adapted to pivot on the upper end of said toggle mechanism 34 to permit the power mechanism 38 to function thereon to supply said fluid pressure actuated power bar preferably with increased leverage to actuate the pressing lever 20.

For this purpose I provide a standard type of bar lever 36 having the front end thereof pivotally mounted as at 40 on a point of the power arm 24 of said pressing lever 16 preferably intermediate its pivot 18 thereof and the rear end thereof. The outer end of said bar lever 36 is adapted to abut the stop 26 for a purpose to be described.

The upper end of said toggle mechanism 34 or whatever type of treadle operated man power actuated means is employed to pivot the pressing lever 16 to a closed pressing position is preferably pivotally connected to the bar lever at a point 46 preferably spaced closer to its point of pivotal connection 40 to the power arm 24 of said pressing lever 16 than to the rear end thereof for a purpose to be described.

It is obvious, however, that for certain features of my invention the bar lever may be omitted and the upper end of said toggle mechanism or other means employed may be connected directly to the power arm 24 of said pressing lever 16. The toggle mechanism for man power operation of said bar lever 36 and/or pressing lever 16 is of a standard type and comprises an upper toggle member 48 having the upper end thereof pivotally connected to said bar lever 36 or power arm 24 as at 46 and a lower toggle member 50 pivoted to the rear end of the frame base as at 52 and having the upper end thereof pivotally attached to the lower end of the upper toggle member 48 as at 54.

Means such as the spring 56 may be provided to normally urge the upper and lower toggle members 48 and 50 to a broken nonpressing position. Said spring 56 mounted on said lower toggle member may be attached either to said frame or to the rear end of the treadle 30.

A rear toggle member 58 is also provided having the rear end attached to the center portion of said lower toggle 50 as at 60 and a front toggle member 62 is also preferably provided pivoted at a point intermediate the ends thereof to the frame as at 64 and having its rear end pivotally attached to the front end of said rear toggle member as at 66.

The rear end of said front toggle member is also preferably provided with a counter weight 68 adapted to assist in raising said toggle mechanism to a locked intermediate position when lifted to a position raising the pivotal point of connection 66 of said front and rear toggle members 62 and 58 respectively upwards past its dead center.

A link 70 is provided pivotally connected at its upper end to the front end of the front toggle member as at 72 and pivotally connected at its lower end to the treadle 30 as at 74, whereby on depression of said treadle 30 said toggle mechanism may function to align said upper and lower toggle members 48 and 50 respectively into a substan-

ce. The upper end of the upper toggle member 48 is pivotally connected to the rear end of the power arm 24 as at 76 and the lower end of the lower toggle member 50 is pivotally connected to the front end of the power arm 24 as at 78.

The treadle 30 is provided with a handle 80 mounted on its rear end and a counter weight 82 mounted on its front end.

The treadle 30 is pivotally connected to the frame as at 84 and the handle 80 is pivotally connected to the treadle 30 as at 86.

The treadle 30 is provided with a stop 88 having its upper end pivotally connected to the frame as at 90 and its lower end pivotally connected to the treadle 30 as at 92.

The treadle 30 is provided with a handle 94 mounted on its rear end and a counter weight 96 mounted on its front end.

The treadle 30 is pivotally connected to the frame as at 98 and the handle 94 is pivotally connected to the treadle 30 as at 100.

The treadle 30 is provided with a stop 102 having its upper end pivotally connected to the frame as at 104 and its lower end pivotally connected to the treadle 30 as at 106.

The treadle 30 is provided with a handle 108 mounted on its rear end and a counter weight 110 mounted on its front end.

The treadle 30 is pivotally connected to the frame as at 112 and the handle 108 is pivotally connected to the treadle 30 as at 114.

The treadle 30 is provided with a stop 116 having its upper end pivotally connected to the frame as at 118 and its lower end pivotally connected to the treadle 30 as at 120.

5 tally rigid and vertical position just short of dead center to raise the bar lever 36 to abut said stop 26 to pivot said pressing lever 16 through said stop 26 and pivot point of attachment 40
 10 of said pressing lever thereto to a closed intermediate pressing position.

15 As stated hitherto, a further feature of my invention includes the means about to be described I preferably employ for holding the specific type 20 of toggle mechanism shown in a raised locked position adjustable from the front of a machine and also providing means for breaking the toggle mechanism for release thereof and consequent opening of the press through the medium of the 25 spring 56 or other means employed. For this purpose an adjustable stop 76 is provided having slots 78 therein which the bolts 80 are adapted to ride for locking said adjustable stop 76 to the front portion of the frame 12 in any desired adjustable position. Said stop 76 is provided with a bumper surface 82. A locking lever 84 is provided having a portion intermediate the ends thereof pivotally mounted on said frame preferably on the same pivot 64 as the front toggle member 62 is pivotally mounted on said frame. A bumper plate 85 is provided on the rear end of said locking lever and is adapted to be contacted by a bumper pad 86 located on the rear portion of said front toggle and to be pivoted 30 upwards thereby when the pivot point 66 of attachment of said front and rear toggle members 62 and 58 respectively has passed by its dead center and pivot the bumper pad 86 on the front of said locking lever 84 against the bumper plate 35 82 on said adjustable stop 76 to function as a locking means for said toggle mechanism 34 in a raised locked position. It is apparent that by adjusting the position of the bracket or stop 76 the locking position of the toggle mechanism 34 may 40 be readily adjusted by raising or lowering a stop 76 from a convenient place in the front of the machine thereby providing an easily accessible and positive adjustment of the locking point of the toggle members through the extension of the 45 locking lever to the front or most accessible part of the frame and mounting of the stop 76 in the front of the frame. The locking lever 84 also functions through a mechanism to be described to break the toggle connection 66 of the front 50 and rear toggle members 62 and 58 respectively by respectively lowering the pivotal point of connection 66 thereof below its dead center, and for this purpose a release and outlet treadle 90 is provided pivotally mounted on said frame as at 55 92. A link 94 has its lower end connected to the rear end of the release and outlet treadle 90 as at 96 and its upper end pivotally connected to the front end of said locking lever 84 as at 98. Said link 94 is preferably provided with the lost motion connection 100 which will be described in 60 more detail later. It is therefore obvious that when the front end of said release and outlet treadle 90 is depressed that the rear end will be raised upward causing the front end of the locking lever 84 to be tilted upwards through the medium of the link 94 and the rear end depressed to cause the pad 85 thereon to contact the plate 86 on the rear end of said front toggle member to knock the pivotal point of attachment 65 66 of said front and rear toggle members 62 and 58 respectively past its dead center to release the toggle mechanism to cause the spring 56 to pivot the pressing lever 16 to move the movable pressing form 20 to an open position.

It is obvious that the adjustable lock provided by the locking lever 84 in front of the pressing frame and the man power release for the man power operated bar actuated mechanism may be provided if desired in a man power operated press without the supplemental features of the fluid actuated power mechanism about to be described.

20 However, I preferably provide supplemental fluid actuated power means 38 to pivot said pressing lever 16 to exert greater than man power pressure on said pressing lever 16 and to this end I preferably pivotally mount a pressure cylinder 102 on the work arm 22 of said pressing lever as at 104. A piston 106 is provided for reciprocation in said cylinder 62 having a piston rod 108 25 projecting rearwardly therefrom. The piston rod 108 is adapted to actuate the bar lever 36 preferably through any type of multiplying mechanism for increasing the leverage, three specific forms having been shown. In the preferred embodiment shown in Figs. 1-5 I pivotally mounted as at 110 on the rear end of said pressing lever power arm 24, a bell crank lever 112 having an upwardly projecting long arm 114 pivotally attached as at 116 to said piston rod 108 and a rearwardly projecting arm 118. A link 120 is pivoted as at 122 to the rear end of said bar lever 36 and its lower end pivotally connected as at 124 to the rearwardly projecting arm 118 of said bell crank lever 112, whereby on actuation of said piston said bell crank lever and link may function to pivot the rear end 42 of said bar lever 36 downwardly to tilt the front end thereof upwardly to raise the power arm of said pressing lever upwardly to exert greater pressure on said work arm 22. In my preferred embodiment it is obvious that actuation of the power mechanism will function also to exert pressure on the work arm 22 of said pressing lever through the pivotal point of connection 104 of the pressure cylinder 102 thereto and upward pressure on the power arm through the medium of the bar lever 36 pivoting on its now rigid pivotal point of attachment 46 of the man power actuated means thereto, rigid because the upper and lower toggle members have been raised to a substantially rigid vertical position, to pivot it, through the pivotal point of connection 40 of the front end of the bar lever 36 to said power arm 24 of said pressing lever, upwards, it being obvious that backward pressure is exerted on the piston rod 108 causing the upwardly extending long arm 114 of said bell crank lever 112 to pivot backwards and through the medium of the rearwardly projecting arm 118 thereof and connecting link 120 pivot the rear end of said bar lever 36 downwards to raise the front end thereof upwards and power arm 24 of said pressing lever 16 upwards through the medium of its pivotal point of connection 40 of the bar lever thereto. It is obvious that an increased leverage action will be secured for several reasons, namely, due to the fact that the pivotal point of connection 46 of the toggle mechanism 34 to said bar-lever 36 is spaced closer to the pivotal point of connection 40 of said bar lever 36 to said power arm than the pivotal point of connection 122 of said link 120 to said bar lever 36, thereby providing increased leverage action by the difference between the lengths of the relative work and power arms of said bar lever now functioning as a pure lever of the first class and by the respective length of the upwardly projecting power arm 114 of said bell crank lever and the rearwardly projecting work arm 118 thereof.

Other types of mechanism for accomplishing the same substantial increased leverage effect are shown in Figs. 6 and 7. In Fig. 6 the bar lever 36 pivots on the point 46 to exert increased pressure on the pressing lever 16 at point 40 and as the result of roller means 130 mounted on the rear end of said piston rod 108 functioning against the upper surface 126 of an oblique slot 128 formed in the rear end of said power arm 24 5 and simultaneously bearing on the upper surface 132 of the bar lever 36. It is thus obvious that the roller means on the rear end of the piston rod 108 functions as a wedge to pivot the rear end of said bar lever 36 downwards and 10 hence the front end of the bar lever upwards and hence power arm of said pressing lever 16 upwards.

I have shown in Fig. 7 a still alternative form of power increasing mechanism wherein the bar lever 36 receives the thrust of the piston rod 108 through the differential toggle members 132 and 134, each having the upper ends thereof pivotally connected to the piston rods 108 as at 136. The link 132 is of shorter length and is pivotally 15 connected as at 138 to the rear end of said bar lever 36. The link 134 is of greater length and is pivotally connected as at 140 to the power arm 24 of said pressing lever. The general design of this mechanism makes it possible to apply very 20 powerful pressure in the embodiment shown in Figs. 6 and 7 without in any way hampering the operation of the press of the treadle operated unit for light pressures only. This is a decided 25 advantage in garment manufacture where the operations require a convenient and optional variation in pressure.

Means are preferably provided to return the piston 106 to a closed initial starting position, said means comprising in my preferred embodiment a spring 142 having a center portion thereof wrapped around the pivot point 110 of said bell crank lever 112, the front end thereof abutting a stop 146 on the power arm 24 of said pressing lever 16 and the rear end thereof abutting the pivotal point of connection 124 of the link 120 to said rear arm 118 of said bell crank lever 112 to move the rearwardly extending arm 118 of said bell crank lever upwards to pivot the upwardly extending arm 114 forwards to pivot 50 the piston rod 108 forwards to move the piston to a forward initial starting position.

It is also apparent that if desired the stop 26 may be omitted, the piston 106 through the action of the bell crank lever 112 or other connecting means employed being moved to abut the front end of the cylinder to hold the rear end of said bar lever 36 in a rigid position to cause it to function as a bar during the man power operation of the toggle mechanism to raise 60 the pressing lever 16 to a closed intermediate pressing position. It is obvious that the spring 142 functions to move the piston 106 forward in the pressing cylinder to exhaust the fluid pressure therein. As stated hitherto, one feature of 65 this portion of my invention is the high safety factor involved as accidental application of power to the piston 106 will not dangerously apply pressure to or cause motion of the pressing lever 16 with the press open as it will merely cause 70 the bar lever 36 and broken toggle mechanism to pivot slightly without causing any downward motion of the pressing form 20, said application of power only functioning to exert pressure on said pressing lever when the rigid pivot point 46 is 75 provided when the upper and lower toggle mem-

bers 48 and 50 have been raised to a rigid substantially vertical substantially closed intermediate pressing position to form a fulcrum 46 for pivotal movement of said bar lever 36 thereon, thus unless the press has been closed and locked by man power in intermediate pressing position by the treadle or otherwise, making it practically impossible for the operative to suffer from the accidental application of power.

Further features of my invention relate to the valve mechanism I preferably employ for controlling the action of the fluid pressure actuated power mechanism. Said means includes pipe means connected to said cylinder 102, specifically a pipe 148 connected to the front end of said cylinder and connected respectively by separate pipes 150 and 152 to the inlet and outlet valves 154 and 156 respectively. The outlet valve 156 discharges through means of the outlet 158 into the atmosphere or to any desired place. The inlet valve 154 is supplied by the pipe 160 from a source of fluid pressure (not shown). The inlet and outlet valves 154 and 156 as shown in Fig. 4 are preferably located adjacent to each other and are provided with the downwardly projecting valve stems 162 and 164 respectively. A cam 166 is provided pivotally mounted as at 168 on the front portion of the frame and provided with the laterally downwardly projecting arms 170 and 172 respectively on each side thereof thereby forming an arcuate cam surface 174 on the lower surface thereof. The upper surface of said cam 166 is provided with the preferably adjustable tappets 176 adapted to bear against said respective inlet and outlet valve stems 162 and 164 respectively. A rocker mechanism 178 is also pivotally mounted as at 180 on the front portion of said frame 12, said rocker mechanism being provided with an arcuate slot 182 in the lower end thereof in which the stop pin 184 mounted on the frame is adapted to function for a purpose to be described. An inlet treadle 186 is pivotally mounted on said frame and has the rear end thereof beyond said pivot point pivotally connected by means of the inlet link 190 to the inlet side 192 of said rocker mechanism 178. As stated hitherto in my preferred embodiment the outlet and man power operated release treadle 90 is pivotally mounted as at 92 on said frame and is pivotally connected by means of the outlet link 191 which has the upper end thereof pivotally connected to the outlet side 198 of said rocker mechanism 178. The rocker mechanism 178 also has the roller 200 mounted on a central vertical upward extension 202 thereof. The cam 166 is designed to have no effect on the roller 200 after the rocker 178 has been moved by the respective treadle, that is when either treadle is depressed the rocker arm rotated and the valves opened. The opposing treadle must be depressed to actuate the valve. The lost motion connection 100 to the press opening mechanism normally reacts on the treadles 186 and 90 to force them in a neutral position with both inlet and outlet valves 154 and 156 closed when the press is brought into a closed position. The slot 182 in the rocker arm 178 is arranged in regard to the stop pin 184 to allow motion of the exhaust treadle to continue for the purpose of opening the press after the exhaust valve 156 has been opened. The cam surfaces of the cam 166 are preferably extended to take care of this extra motion of the rocker arm 178 and its cam surface 174 and prevent the roller 200 from running off the cam surface 174.

For purposes of illustration points 1, 2, 3 and 4 are designated on the cam surface 174 and the sequence of operation is as follows in regard to the treadles and their associated parts. On depression of the exhaust treadle the roller is moved from position one to position two on said cam. During this interval the inlet valve 154 is closed by the tappet 176. By moving the roller from position two to position three on the cam, the opposite side of the cam is lifted up to open the exhaust valve 156. During the moving of the rollers from position one to position three respectively, including the respective closing of the inlet valve and opening of the exhaust valve the surfaces 204 and 206 of the lost motion connection 100 are brought adjacent to each other, thereby providing a true lost motion. As the roller is moved from position three to position four on the cam however, the surface 206 contacts the surface 204 to raise up the link 94 to pivot the locking lever 84 to break the toggle mechanism 34 for man power actuation of the cam when the spring 56 or other means employed will function to open the press. The particular arrangement of lost motion connection, valves, etc., will result in completely closing the inlet valve and opening the exhaust valve before the press can be opened by the release treadle 90, thereby providing a safety factor and preventing the press from being opened by man power while there is any pressure at all in the power mechanism, thereby eliminating any dangerous recoil on the power mechanism by release of pressure when the press is opened and eliminating the possibility of unlocking the press while under heavy pressure as the resultant recoil is dangerous to the operator and harmful to the pressing machine. When, however, the power treadle is actuated after locking of the man power actuated mechanism in intermediate position it will first move the roller from position four to three on the cam, the lost motion will function with no resultant actuation of the inlet or exhaust valves. When, however, the roller is moved from position three to two, the tappet 176 functions to close the exhaust valve and when the roller is moved from a position from two to one on the cam the cam is tilted to permit the other tappet 176 to open the inlet valve, thereby providing the desirable sequence of closing the exhaust valve before any pressure is admitted to the cylinder for the proper application of power thereto.

It is therefore obvious that in my improved combination that the specific type of locking means for the man power actuated toggle mechanism functions to lock the press in a closed position to permit the power mechanism to function and that the power mechanism will not function to produce any useful pressing result, or dangerous movement of the pressing lever unless the press is closed to a man power actuated locked intermediate pressing position. It is also obvious that the means I employ for unlocking the man power actuated pressure operating mechanism functions to close the inlet valve, open the exhaust valve through a lost motion connection thereby eliminating recoil prior to any man power actuated opening of the press, and it is also apparent that with my improved construction of bar lever it is enabled to function as a bar in the ready man power closing of the press to an intermediate pressing position and to pivot on the man power actuated closing means to function preferably as a leverage increasing mechanism for the power actuation of

the press and it is obvious that all the various features of my invention hitherto described function in combination with each other to produce an efficient type of press with the safety factor of preventing unlocking of the device when the power is on and preventing the accidental application of power for moving the press when in open position. It is apparent therefore that I have provided a novel type of press useful for garment or laundry presses with the advantages described above.

Inasmuch as linear pressure is applied on the piston it is obvious that it will apply substantially the same amount of pressure, regardless of the thickness of the material being pressed.

It is understood that my invention is not limited to the specific embodiments shown and that various deviations may be made therefrom without departing from the spirit and scope of the appended claims.

What I claim is:

1. In a garment press, a frame, a stationary pressing form, a pressing lever of the first class pivotally mounted on said frame having a pressing form mounted on the work arm thereof, toggle mechanism for man power operation of said lever comprising an upper toggle member pivotally connected to said pressing lever power arm, a lower toggle member pivoted to the frame base and upper toggle member, a rear toggle member pivoted to said toggle mechanism, a front toggle member pivotally mounted between the ends thereof on said frame and having its rear end pivotally connected to the front end of said rear toggle member, a treadle pivotally mounted on said frame and means pivotally joining said treadle with the front end of said front toggle member, a stop mounted on the front of said frame, a locking lever pivotally mounted intermediate its ends on said frame adapted to be abutted by said front toggle member to pivot said locking lever until the front end thereof abuts the stop when the point of connection of said front and rear toggle members is beyond its dead center to retain said pressing lever in locked actuating position, a release treadle pivoted intermediate its ends on said frame and a link pivoted to the front end of said locking lever and the rear end of said release treadle to cause the rear end of the locking lever to lower the point of connection of said front and rear toggle members below its dead center to release said toggle mechanism.

2. In a garment press, a frame, a stationary pressing form, a movable pressing form, a treadle pivotally mounted on said frame and mechanism pivotally joining said treadle with said movable form, a stop mounted on the front of said frame, a locking lever pivotally mounted on said frame having the rear end thereof adapted to be abutted by a portion of said mechanism and pivot said locking lever until the front end thereof abuts the stop to retain said movable pressing form in locked pressing position, a release treadle pivoted on said frame and a link pivoted to the front end of said locking lever and the rear end of said release treadle to cause the rear end of the locking lever to abut and release said mechanism.

3. In a garment press, a frame, a stationary pressing form, a movable pressing form, mechanism for man power operation of said movable pressing form, a treadle pivotally mounted on said frame, means pivotally joining said treadle

with said man power operated mechanism, a stop mounted in the front of said frame, a locking lever pivotally mounted on said frame having the rear end thereof adapted to be abutted by said man power operated mechanism and pivot said locking lever until the front end thereof abuts the stop to retain said mechanism in an off center movable pressing form actuating position, a release treadle pivoted on said frame 10 and a link pivoted to the front end of said locking lever and rear end of said release treadle to cause the rear end of said locking lever to move said man power actuated mechanism to actuate it and to permit the movable pressing form to 15 rise to an open position.

4. In a garment press, a frame, a stationary pressing form, a pressing lever of the first class pivotally mounted on said frame having a pressing form mounted on the work arm thereof, a 20 bar lever having its front end pivotally attached to the power arm of said pressing lever and having its free end restrained against upward movement by said pressing lever, mechanism for man power operation of said pressing lever pivotally 25 attached to said bar lever at a point spaced nearer to the pivot point thereof on said pressing lever power arm than to the rear end thereof, said point being adapted on actuation of said man power mechanism to assume a fixed position relative to said bar lever, a treadle pivotally mounted on said frame, means to connect said treadle to said pressing lever operating mechanism, whereby on depressing of said treadle said man power actuated mechanism may function to raise 30 said bar lever to pivot said pressing lever upwards, supplemental fluid pressure actuated power means to pivot said pressing lever comprising a pressure cylinder pivotally mounted on said pressing lever, a piston movable therein having 35 a rod projecting rearwardly therefrom, a bell crank lever pivotally mounted on said pressing lever power arm having an upwardly projecting arm pivotally attached to said piston rod rear end and a rearwardly projecting arm, a link pivotally joining the rear end of said bar lever and rearwardly projecting bell crank lever arm, whereby on actuation of said piston said bell 40 crank lever and link may function to pivot the rear end of said bar lever downwardly to tilt the front end upwardly about the now fixed pivot to raise the power arm of said pressing lever upwardly to exert a greater pressure on said work arm and valve mechanism for controlling the action of said fluid pressure mechanism.

5. In a garment press, a frame, a stationary pressing form, a pressing lever of the first class pivotally mounted on said frame having a pressing form mounted on the work arm thereof, toggle mechanism for man power operation of said pressing lever comprising an upper toggle member connected to said pressing lever power arm, a lower toggle member pivoted to the frame base and upper toggle member, a rear toggle member pivoted to said toggle mechanism, a front toggle member pivotally mounted on said frame and having its rear end pivotally connected to the front of said rear toggle member, a treadle pivotally mounted on said frame, means pivotally joining said treadle with the front end of said front toggle member, a stop mounted on the front of said frame, a locking lever pivotally mounted on said frame adapted to be abutted by said front toggle member to pivot said locking lever until the front end thereof abuts the stop, 70 a release and outlet treadle pivoted on said frame 75

and a link pivoted to the front arm of said locking lever and having a lost motion connection with the rear end of said release treadle to cause the locking lever to lower said front and rear toggle member connection, supplemental fluid pressure actuated power means to pivot said pressing lever to exert a greater than man power pressure on said pressing lever, valve mechanism for controlling the action of said fluid pressure mechanism, and an inlet treadle for said valve mechanism, said outlet and release treadle lever being also connected to said valve mechanism to open the outlet thereof, prior to taking up said lost motion connection.

6. In a garment press, a frame, a stationary pressing form, a pressing lever of the first class pivotally mounted on said frame having a pressing form mounted on the work arm thereof adapted to be moved into pressing relationship with said stationary pressing form, a bar lever having a front end pivotally attached to the power arm of said pressing lever and having its free end restrained against movement by said pressing lever, mechanism for man power operation of said pressing lever pivotally attached to a point on said bar lever intermediate its ends and means rendering said mechanism capable of retaining a maximum man power pressure position to provide a rigid pivot for said bar lever to permit pivotal movement thereof, and supplemental power means mounted on said pressing lever functioning against the free rear end of said bar lever by means providing an increased leverage to pivot it on its point of attachment to said man power actuated mechanism to exert greater than man power pressure on said pressing form, and mechanism for controlling the action of said power mechanism.

7. In a garment press, a frame, a stationary pressing form, a pressing lever of the first class pivotally mounted on said frame having a pressing form mounted on the work arm thereof, said pressing form being adapted to be moved into pressing relationship with said stationary pressing form, a bar lever having an end pivotally attached to the power arm of said pressing lever and having its free end restrained against movement by said pressing lever, a pressure cylinder pivotally mounted on said pressing lever, and a piston movable therein having a rod projecting therefrom operatively connected by means providing an increased leverage both with the free end of said bar lever and with the pressing lever power arm to exert downward pressure on the connected work arm.

8. In a garment press, a frame, a stationary pressing form, a pressing lever of the first class pivotally mounted on said frame having a pressing form mounted on the work arm thereof adapted to be moved into pressing relationship with said stationary pressing form, a bar lever having an end pivotally attached to said pressing lever and being pivotally mounted on means projecting upwardly from said frame, a pressure cylinder pivotally mounted on said pressing lever, a piston movable therein having a rod projecting therefrom, a bell crank lever pivotally mounted near the rear end of said pressing lever power arm having a projecting arm pivotally attached to said piston rod end and a shorter projecting arm, and a link pivotally joining the bar lever and shorter projecting bell crank lever arm.

9. In a garment press, a frame, a stationary pressing form, a pressing lever of the first class pivotally mounted on said frame having a press-

ing form mounted on the work arm thereof and having a rearwardly downwardly inclined slot near the rear end of said lever, said movable pressing form being adapted to be moved on 5 movement of said lever into pressing relationship with said stationary pressing form, a bar lever having one end pivotally attached to the power arm of said pressing lever and pivotally mounted on means projecting upwardly from said frame, 10 a pressure cylinder pivotally mounted on said pressing lever, a piston movable therein having a rod projecting rearwardly therefrom having roller means adapted to slidably engage said slot and upper surface of said bar lever rear end to 15 exert a downward pressure on the connected work arm to force the movable pressing form mounted on said pressing lever into pressing relationship with said stationary form.

10. In a garment press, a frame, a stationary 20 pressing form, a pressing lever of the first class pivotally mounted on said frame having a pressing form mounted on the work arm thereof adapted to be moved into pressing relationship with said stationary pressing form, a bar lever 25 pivotally mounted on the power arm of said lever and also pivotally mounted on means projecting upwardly from said frame, a pressure cylinder pivotally mounted on the work arm of said pressing lever, a piston movable therein having a rod 30 projecting rearwardly therefrom, a link pivotally connecting the piston rod rear end to said pressing lever power arm and a link pivotally connecting the piston rod rear end to said bar lever rear end inclined toward the rear of said bar lever at 35 an angle relative to the perpendicular between said pivotal point of connection on said piston rod rear end and said bar lever.

11. In a garment press, a frame, a stationary 40 pressing form, a pressing lever of the first class pivotally mounted on said frame having a pressing form mounted on the work arm thereof adapted to be moved into pressing relationship with said stationary pressing form, a bar lever having an end pivotally attached to the power 45 arm of said pressing lever, and pivotally mounted between its ends on means projecting upwardly from said frame, expansible power means pivotally mounted on said pressing lever and having an expansible portion connected by link means including said bar lever to the bar lever to provide 50 an increased leverage on said bar lever and means to expand said means to move said bar lever to move the pressing lever form into power pressing relationship with said stationary form.

55. 12. In a garment press, a frame, a stationary pressing form, a pressing lever of the first class pivotally mounted on said frame having a pressing form mounted on one arm thereof adapted to be moved into pressing relationship with said 60 stationary pressing form, a bar lever having an end pivotally mounted on said pressing lever and pivotally mounted between its ends on means projecting upwardly from said frame, expansible power means pivotally mounted on said pressing 65 lever and having an expansible portion connected by linkage including said pivotally mounted bar lever to said bar lever, and means to expand said means to move said bar lever to move the pressing lever form into power pressing relationship with said stationary form.

70. 13. In a pressing machine, a stationary pressing form, a lever of the first class mounted on said machine, having a pressing form mounted thereon to be brought into pressing relationship 75 with said stationary pressing form, a bar lever

having one end thereof pivotally connected to said pressing lever, and the other end thereof constrained against upward movement, mechanism for man power actuation of said machine connected to an intermediate point on said bar lever whereby actuation of said man power mechanism may raise said bar lever to tilt said pressing lever to bring the pressing form thereof into a maximum, man power actuated pressing relationship with said stationary pressing form, means to retain said man power actuated mechanism, bar lever and pressing lever in said position, power mechanism, means connecting said power mechanism to said other end of said bar lever to pivot it on actuation of said power mechanism to cause said bar lever to pivot on said then rigid point of connection to said man power actuated mechanism as a fulcrum to pivot said opposite pressing lever connected bar lever end to apply power pressure to said connected lever and 20 pressing form.

14. In a pressing machine, a stationary pressing form, a lever of the first class mounted on said machine having a pressing form mounted thereon to be brought into pressing relationship with said stationary pressing form, a bar lever having one end thereof pivotally connected to said pressing lever, and the other end thereof constrained against upward movement, mechanism for man power actuation of said machine 25 connected to an intermediate point on said bar lever whereby actuation of said man power mechanism may raise said bar lever to tilt said pressing lever to bring the pressing form thereof into a maximum, man power actuated pressing relationship with said stationary pressing form, means to retain said man power actuated mechanism, bar lever and pressing lever in said position, power mechanism, means connecting said power mechanism to said other end of said bar lever to 30 pivot it on actuation of said power mechanism to cause said bar lever to pivot on said then rigid point of connection to said man power actuated mechanism as a fulcrum to pivot said opposite pressing lever connected bar lever end to apply power pressure to said connected pressing lever and pressing form, the bar lever being so connected to said movable pressing form, power mechanism and man power actuated mechanism as to permit said power mechanism to apply increased leverage through said bar lever to said 40 movable pressing form.

15. In a garment press, a frame, a stationary 45 pressing form, a movable pressing form, an operating lever pivotally mounted on the frame, and overlocking toggle mechanism connecting said operating lever and movable pressing form, a stop mounted on said frame, a locking lever pivotally mounted on said frame having one end thereof adapted to be abutted by said overlocking toggle mechanism, so that when said overlocking toggle mechanism is moved past dead center said locking lever will be pivoted until the other end abuts the stop to retain said overlocking toggle mechanism in off center position and thereby to retain 50 said movable pressing form in pressing relationship with said stationary pressing form, a release lever pivoted on said frame operatively connected to said locking lever to pivot said locking lever to remove said overlocked toggle mechanism from its overlocked position to release it and thereby 55 to permit the movable pressing form to rise to an open position.

16. In a garment press, a frame, a stationary 60 pressing form, a pressing lever of the first class 65

- 5 pivotally mounted on said frame having a pressing form mounted on the work arm thereof, adapted to be moved into pressing relationship with said stationary pressing form, a bar lever having a front end pivotally attached to the power arm of said pressing lever and having a free end, mechanism for man power operation of said pressing lever pivotally attached to a point on said bar lever intermediate its ends and means rendering 10 said mechanism capable of retaining a maximum man power pressure position to provide a rigid pivot for said bar lever to permit pivotal movement thereof, and supplemental power means mounted on said pressing lever and connected to 15 the free end of said bar lever to pivot it on its point of attachment to said man power actuated mechanism to exert greater than man power pressure on said pressing form, and mechanism for controlling the action of said power mechanism.
17. In a garment press, a frame, a stationary pressing form, a pressing lever of the first class pivotally mounted on said frame having a pressing form mounted on the work arm thereof, said 20 pressing form being adapted to be moved into pressing relationship with said stationary pressing form, a bar lever having an end pivotally attached to the power arm of said pressing lever and having a free end, a pressure cylinder pivotally mounted on said pressing lever, and a piston movable therein having a rod projecting rearwardly therefrom operatively connected both with the free end of said bar lever and with the pressing lever power arm to exert downward pressure on the connected work arm.
18. In a garment pressing machine, a frame, cooperating pressing elements, one of which is movable toward and from the other, a lever pivoted between its ends to the frame and carrying 25 the movable element on one arm thereof, actuating mechanism for the lever including a motion transmitting part and differential connections between the motion transmitting part and the other arm of the lever, said connections including a second lever pivoted to the latter arm of the first lever, means on the first lever for holding the second lever from pivotal movement relative to the first lever during the preliminary closing of the press and said connections including means for fulcruming the second lever after the press has been preliminarily closed, thereby permitting relative movement of the second lever to the first lever by the actuating part, when the press is 30 preliminarily closed.
19. In a garment pressing machine, a frame, cooperating pressing elements, one of which is movable toward and from the other, a lever pivoted between its ends to the frame and carrying the movable element on one arm thereof, actuating mechanism for the lever including a motor, a part actuated by the motor, a member mounted on a pivot on the other arm of said lever capable of movement with the lever as a unit and relatively thereto about said pivot, said member being connected to said part which is actuated by the motor to receive motion therefrom, and means on the lever for holding said member from movement about its pivot relatively to the lever during the preliminary closing of the press and permitting movement thereof about its pivot relatively to the lever during the final closing of the press, means providing a second pivot for said member after the movable press element has been 35 preliminarily closed, said movement being effected by said part which is actuated by the motor, said last means causing said relative movement to effect final closing of the press.

PYAM L. PENDLETON.
